[57] **CLAIM**

The ornamental design for auxiliary sides for utility trailer, as shown and described.

DESCRIPTION

FIG. 1 is a perspective view of the auxiliary sides for utility trailer showing my new design, it being understood that the broken lines are for illustrative purposes only;

FIG. 2 is a side elevational view thereof, the side opposite being substantially a mirror image of that shown;

FIG. 3 is a top plan view thereof;

FIG. 4 is a bottom plan view thereof;

FIG. 5 is a front elevational view thereof;

FIG. 6 is a rear elevational view thereof;

FIG. 7 is a side elevational view of the auxiliary sides for utility trailer showing a second embodiment of my new design, the opposite side being a mirror image of that shown;

FIG. 8 is a front elevational view of the embodiment of FIG. 7; and

FIG. 9 is a rear elevational view of the embodiment of FIG. 7.

FIG. 1

FIG. 2

FIG. 5

FIG. 3
